UNITED STATES PATENT OFFICE.

LAWRENCE E. JOHNSON, OF MELROSE, EDWARD ERICKSON, OF LYNN, AND OTTO T. PETERSON, OF MALDEN, MASSACHUSETTS.

PRESSER-FOOT MECHANISM FOR SEWING-MACHINES.

1,357,237.

Specification of Letters Patent.

Patented Nov. 2, 1920.

Application filed December 12, 1919. Serial No. 345,428.

To all whom it may concern:

Be it known that we, LAWRENCE E. JOHNSON, a citizen of the United States of America, and a resident of Melrose, in the county of Essex and Commonwealth of Massachusetts, EDWARD ERICKSON, a subject of the Republic of Finland, and a resident of Lynn, in the county of Essex and Commonwealth of Massachusetts, and OTTO T. PETERSON, a citizen of the United States of America, and a resident of Malden, in the county of Middlesex and Commonwealth of Massachusetts, have invented certain new and useful Improvements in Presser-Foot Mechanism for Sewing-Machines, of which the following is a specification.

This invention relates to improvements in presser-foot mechanisms for shoe-sewing machines in which provision is made for automatically regulating the length of thread to be drawn from the source of supply in accordance with the various thicknesses of material being operated upon.

The present invention is an improvement upon the invention shown and described in Letters Patent No. 1,133,149 issued to Lawrence E. Johnson and Edward Erickson Mar. 23, 1915.

In the device of the patent above referred to, the presser-foot is secured to a support slidably mounted in a cam-operated lever adapted to be actuated to release the pressure of the presser-foot when the work is being fed.

The slidable support is adapted also to slide transversely of the lever in order to accommodate the presser-foot to varying thicknesses of material.

It is essential that when the support is given this additional movement transversely of the lever, there should be no cramping thereof which would prevent the support from sliding freely.

The object of the present invention is to provide a means for attaining this result.

The invention consists primarily in providing an adjustable abutment with which the slidable support contacts when the presser-foot is lifted which abutment is slightly yieldable under sufficient spring

tension to prevent the slidable support from tilting in its bearing and thereby binding on the walls of the bearing sufficiently to prevent the required adjustment of said support.

The invention further consists in so constructing the abutment and its support that it will not interfere with the operation of said sliding support during the ordinary operation of the machine upon material of even thickness, the presser-foot being free to coact with the work and be lifted therefrom without engagement with said abutment.

The invention further consists of certain novel features of construction and arrangement of parts which will be readily understood by reference to the description of the drawings and to the claims to be herein-after given.

For the purpose of illustrating the invention, one preferred form thereof is illustrated in the drawings, this form having been found to give satisfactory and reliable results although it is to be understood that the various instrumentalities of which the invention consists can be variously arranged and organized and the invention is not limited to the precise arrangement and organization of these instrumentalities as herein shown and described, except as required by the scope of the appended claims.

Of the drawings:

Figure 1 represents a vertical section of a portion of a shoe-sewing machine showing the present invention applied thereto, and

Fig. 2 represents a sectional detail to be hereinafter referred to.

Similar characters indicate like parts throughout the several figures of the drawings.

In the drawings, 10 is a portion of the frame of a shoe sewing-machine in which is revolubly mounted a shaft 11 having a cam disk 12 secured thereto.

Secured upon the frame 10 in the usual manner, is a work support 13 which may be of any well-known construction.

Fixedly secured in the frame 10 is a rod 14 and over this rod extends a thread t

drawn from any suitable source of supply. The thread *t* then passes around a pin 15 secured to the thread lock cam lever 16 which is pivoted at 17 and has at its rear end 5 a roller 18 in the cam path 19 formed in one side of the cam disk 12.

The thread *t* passes from the pin 15 over a stationary pin 20 and then through slots in the downwardly extending arms 21 of a 10 forked member 22.

The thread *t* passes from one arm 21 to the other arm 21 under a stud or pin 23 projecting horizontally from the side of the forward end of the lever 16.

15 From the forked member 22 the thread *t* passes through a hole 24 in the movable frame 25 to the usual wax-pot of a sewing-machine.

The cam disk 12 is provided on its outer 20 face with a cam path 26 in which is positioned a roller 27 mounted on the end of the lever 28 pivoted at 29, and provided at its outer end with a transverse groove 30 in which is mounted the slidable forked member 22 having rack teeth 31 formed in one 25 edge thereof.

The pivot 29 is provided with a gear 32 on its inner end, the teeth of which mesh with the rack teeth 31 of the slidable member 22.

30 The plate 33 secured to the end of the lever 28 prevents the displacement of the member 22.

This rack member 22 is provided with a 35 forwardly extending arm 34 having adjustably secured to the outer end thereof, the presser-foot 35.

The arm 34 has a shoulder 36 formed thereon coacting with the upper face of the 40 lever 28 to limit the downward movement of said member 22. The member 22 is also provided with an upward extension 37 between the upper end of which and the lever 28, is a helical spring 38 which tends to retain the presser-foot 35 in its normal position 45 and against the tension of which said presser-foot is adapted to be lifted.

Secured to the pivot 29 is an arm 39 adapted to be manually operated to adjust 50 the presser-foot 35 relative to the lever 28 and to accommodate it to varying thicknesses of material.

This is accomplished by the operator moving the arm 39 and thereby turning the pinion 32, raising and lowering the presser-foot 55 at will.

When any work is placed upon the support 13, the operator adjusts the presser-foot 35 in the manner just referred to so that it 60 will press upon the upper face of the work, after which it will be automatically adjusted as the material varies in thickness.

Owing to the fact that the slidable member 22 is located outside of the pinion 32 and

between it and one of the guide walls of the 65 transverse groove 30 formed in the lever 28, any movement imparted to said lever 28 by the cam path 26, will be transmitted to the presser-foot 35 thereby removing it from the work when it is desired to feed the latter, or exerting a gripping pressure when the work has been fed.

The main portion of the cam path 26 retains the operating face of the presser-foot 70 75 35 in contact with the work on the support 13 and causes it to exert a gripping pressure thereon, but when it is desired to move the work along the support, the roller 27 of the lever 28 moves into the portion 40 of the cam path 26 thereby causing the presser-foot 80 85 to be lifted from the work temporarily while the work is being moved into a new position.

When the presser-foot is moved downwardly by the cam-controlled lever 28, the work will be securely gripped thereby 85 against the support 13, the lower face of the presser-foot 35 being forced into the face of the work by the cam 12.

The machine is so built that the member 22 will be crimped between the opposite 90 walls of the transverse guide groove 30 when the lever 28 is moved about its pivot 29. Just prior to the roll 27 entering the throw 40 to release the gripping pressure upon the work, the pinion 32 is locked to 95 prevent any sliding movement of the member 22.

Consequently, when the roller 27 enters the throw 40, the presser-foot 35 will be bodily lifted from the work and will remain 100 free from contact therewith until the completion of the feeding operation when it will be released and the spring 38 will be permitted to return the presser-foot into light contact with the work before the roll 27 enters 105 the concentric portion of the cam 26 to produce the gripping pressure upon the work.

It is obvious that when the slidable member 22 is moved transversely of the outer 110 end of the lever 28, the lower operating face of the presser-foot 35 will remain constantly in parallelism, in whatever position said presser-foot may be, relative to the lever 28 and when the lever 28 is in position to grip the work, said operating face is constantly 115 in parallelism with the work support 13 regardless of the thickness of the material being acted upon.

This operating face of the presser-foot 120 will only assume a position at an angle to the work support 13 when the presser-foot is lifted by the action of the throw 40 upon the roller 27 at the rear of the lever 28 to permit the work to be fed. At all times 125 when the roller 27 is in the concentric portion of the cam path 26, the operating face of the presser-foot 35 is parallel with the

face of the work support 13 and this is true regardless of the position of said presser-foot 35 relative to the lever 28 at this time.

When the throw 40 operates the lever 28, 5 the operating face of the presser-foot 35 will be removed entirely from the work and held in this position until the work has been fed, after which the operating face will be returned into light contact with the work 10 by means of the spring 38, the tension of which is only sufficient to position said presser-foot 35 without exerting any gripping pressure upon the work.

When the machine is in operation, the 15 shoulders 36 of the member 22 will be separated from the upper face of the lever 28 and the operating face of the presser-foot 35 will be held by the spring 38 in light contact with the work until the first stitch 20 has been formed. When the lever 28 is moved about its pivot by the throw 40, the presser-foot 35 will be lifted free from contact with the work and will be held in elevated position until the work has been fed. 25 At the conclusion of the work-feeding operation, the spring 38 will force the operating face of the presser-foot 35 into light contact with the work, this action occurring while the roll 27 is still in the throw 40. As the roll 27 moves into the concentric portion of the cam 26, the operating face of the presser-foot 35 will be forced into the material and a gripping pressure exerted thereon.

When the cam 26 acts on the left end of the lever 28 this lever will be moved about its pivot 29 and carry the members 22 and 35 therewith, the presser-foot 35 being caused thereby to give a gripping pressure 40 upon the work on the support 13. This action is due largely to the location of the pivot 29 adjacent to the sliding member 22 so that when said lever 28 is moved about its pivot while the presser-foot 35 is in contact with the work, the slide 22 will be cramped between the walls of the transverse groove 30 on the lever 28 and by this cramping operation said slide will be prevented from moving transversely of the lever 28.

Consequently, when the left hand end of the lever is moved upwardly by the cam 26, the operating face of the presser-foot 35 will be forced into the yielding material upon the work support 13 and firmly grip 55 the same. While the work is gripped in this manner, the needle enters the material and a stitch is formed. Subsequently, while the work is still gripped, the awl is moved to the right and then pierces the material. 60 While the awl is still in the material the roller 27 will enter the throw 40 and cause the gripping pressure of the presser-foot to be released, and the operating face thereof will be lifted from the work preparatory 65 to another feeding of the same, this feeding

being accomplished by the movement of the awl to the left.

The pin 23 is adapted to move in the forked end of the member 22, said pin being moved by the action of the cam path 70 19 on the lever 16 in the end of which said pin is mounted.

The cam path 19 is provided with a throw adapted to oscillate the lever 16 at the proper time to measure off the given quantity of thread for the stitch, the pin in doing this moving longitudinally of the slot 75 in the end of the member 22.

As the thread *t* in crossing this slot passes beneath the pin 23, it is obvious that if the 80 slideable member 22 was always in the same position, a given length of thread would always be measured by the oscillation of the lever 16 and the movement of the pin 23.

It is desired, however, to measure off different lengths of thread for different thicknesses of material and this is readily accomplished by means of the slideable member 22, it being self-evident that when the presser-foot 35 is raised the thread-carrying passages in the arms 21 of the member 22, are similarly raised to a new position corresponding with the thickness of the material and when in this raised position a greater quantity of thread will be drawn from the 90 source of supply by the movement of the pin 23 in the forked end of the member 22, the lowermost position of said pin being the same under all conditions.

It is obvious that this thread measuring 100 device will operate after the presser-foot 35 has returned into contact with the work. When the takeup device is operating, the pin 23 will be in its highest position and the pin 15 will be in position to coat with the 105 pin 20 to lock the thread to prevent it from being fed from the source of supply.

The roller 18 is of less diameter than the width of the cam path 19 and is in contact with the inner wall of said path only when the lever 16 is being moved about its pivot to measure the thread. The roller 18 never contacts with the opposite wall of said path. The pivot member 17 has secured to its outer end an arm 17^a to the end of which is secured a spring 17^b, the opposite end of which is fastened to the framework of the machine, all as described in the patent hereinbefore referred to.

This spring retains the pin 15 in contact 120 with the pin 20 except during the thread measuring operation. When the pins 15 and 20 are in contact the roller 18 is in contact with neither wall of the cam path 19. When in the rotation of the cam 12, 125 the throw of the cam path 19 comes into contact with the roller 18, the lever 16 will be moved about the pivot 17 and the pins 15, 20 will be separated. When the roller 18 again enters the concentric portion of 130

cam path 19 it will be in position free from either wall of said cam paths being retained in this position by the spring 17^b holding the pins 15, 20 in contact.

- 5 Mounted upon the fixed rod 14 is a split block 41 having a clamping bolt 42 mounted therein by which said block 41 may be securely clamped in adjusted position about the axis of said rod 14. This block 41 has 10 upwardly extending ears 43 in which is mounted a stud 44 forming a pivot for a stop member 45.

This stop member 45 has disposed at its upper end a stud 46 on which is mounted a 15 revolute wheel 47.

The stop member 45 has its forward lower end in contact with the upper face of the block 41 thereby preventing forward movement of said member 45 about the axis 20 of the pivot 44.

The rear end of the stop member 45 is separated from the upper face of the block 41 as shown in Fig. 1 of the drawings, and said member 45 is normally retained in the 25 position indicated in said Fig. 1 by means of the spring 48 disposed within a socket in the block 41 and bearing against the under edge of the member 45.

When the roller 27 is in the concentric 30 portion of the cam path 26 and the presser-foot 35 is in gripping contact with the work, the upper extension 37 of the member 22 is removed from the revolute wheel abutment 47 as indicated in Fig. 2 of the drawings.

35 When the roller 27 enters the throw 40 of the cam path 26 and the presser-foot 35 is lifted from the work, the upward extension 37 of the slidable member 22 will come into contact with the revolute wheel abutment 47 and further rear movement of said extension 37 is prevented.

40 As a result of this construction, the slid- 45 able member 22 may be crimped between the opposite walls of the transverse groove 30 when it is desired to move the presser-foot 35 by the oscillation of the lever 28 but when it is desired to effect the sliding move- 50 ment of the member 22 relatively to the lever 28, the crimping of the member 22 against the opposite walls of the transverse groove 30 is prevented by the contact of the upward extensions 37 with the revolute abutment 47.

55 It is obvious from an inspection of the drawings that this abutment is slightly yielding against the tension of the spring 48 and the entire block 41 with the stop member 45 and revolute abutment 47 there- 60 on may be adjusted about the axis of the fixed rod 14 to vary the position of said abutment relatively to the extension 37.

When the awl has penetrated the leather and begins to feed the work and during the entire feeding operation the roller 47 abuts 65 the arm 37 and prevents the upward pres-

sure on the presser-foot from cramping the slidable member 22 against the walls of the transverse slot 30.

This is due to the fact that when the roller 47 is in action and coacting with the 70 part 37, the lower part of the slidable mem- 75 ber 22 will be centered in the transverse groove 30 so that it can move freely.

The cam movement is so arranged as to 80 release the pressure of the roller 47 on the 75 arm 37 as the awl is being released from the leather after the piercing and feeding movement has been completed thereby per- 85 mitting the presser-foot to drop automatically.

In other words, by the use of the present 85 invention, the cramping of the presser-foot support in its operating lever is permitted when such cramping is desired in the opera- 90 tion of the machine and is prevented when in the operation it is desirable to have said presser-foot support freely slide trans- 95 versely of its operating lever.

It is self-evident that by adjusting the 90 block 41 on the rod 14, the revolute abut- 95 ment 47 may be positioned so that the side walls of the slidable member 22 will be in perfect parallelism with the opposite walls of the transverse groove 30 of lever 28 when the operation of the machine requires the 95 member 22 to be adjusted transversely of the operating lever 28.

It is believed that the operation and many 100 advantages of the invention will be readily understood without further description.

Having thus described our invention, we claim—

1. In a shoe-sewing machine, the combina- 105 tion of a work support; a presser-foot; a slidable support therefor; a spring acting on said support; a cam-controlled lever car- 110 rying said slidable support; and an abutment with which said slidable support is adapted to coact when the presser-foot is in raised position.

2. In a shoe-sewing machine, the combina- 115 tion of a work support; a presser-foot; a slidable support therefor; a spring acting on said support; a cam-controlled lever car- 120 rying said slidable support; and a revolute abutment with which said slidable support is adapted to coact when the presser-foot is in raised position.

3. In a shoe-sewing machine, the combina- 125 tion of a work support; a presser-foot; a slidable support therefor; a spring acting on said support; a cam-controlled lever car- 130 rying said slidable support; and a yielding abutment with which said slidable support is adapted to coact when the presser-foot is in raised position.

4. In a shoe-sewing machine, the combina- 130 tion of a work support; a presser-foot; a slidable support therefor; a spring acting on said support; a cam-controlled lever carry-

ing said slidable support; and a spring pressed abutment with which said slidable support is adapted to coact when the presser-foot is in raised position.

5. In a shoe-sewing machine, the combination of a work support; a presser-foot; a slidable support therefor; a spring acting on said support; a cam-controlled lever carrying said slidable support; a fixed rod

10 in the frame of the machine; a block adjustably mounted upon and secured thereto; a stop member pivoted to said block and having limited forward movement about its pivot; and a spring normally retaining said member in its forward position.

6. In a shoe-sewing machine, the combination of a work support; a presser-foot; a slidable support therefor; a spring acting on said support; a cam-controlled lever carrying said slidable support; a fixed rod in the frame of the machine; a block adjustably mounted upon and secured thereto; a stop member pivoted to said block and having limited forward movement about its pivot; a spring normally retaining said member in its forward position; and a wheel revolute in the outer end of said stop member.

7. In a shoe-sewing machine, the combination of a work support; a slidable member having an upward extension and a forwardly projecting arm; a presser-foot on said arm; a spring acting on said member; a cam-controlled lever carrying said slidable member; and an abutment with which said extension is adapted to contact when said presser-foot has been lifted from the work.

8. In a shoe-sewing machine, the combination of a work support; a slidable member having an upward extension and a forwardly projecting arm; a presser-foot on said arm; a spring acting on said member;

a cam-controlled lever carrying said slidable member; and a revoluble abutment with 45 which said extension is adapted to contact when said presser-foot has been lifted from the work.

9. In a shoe-sewing machine, the combination of a work support; a slidable member having an upward extension and a forwardly projecting arm; a presser-foot on said arm; a spring acting on said member; a cam-controlled lever carrying said slidable member; and a yielding abutment with 55 which said extension is adapted to contact when said presser-foot has been lifted from the work.

10. In a shoe-sewing machine, the combination of a work support; a slidable member having an upward extension and a forwardly projecting arm; a presser-foot on said arm; a spring acting on said member; a cam-controlled lever carrying said slidable member; and an adjustable abutment 65 with which said extension is adapted to contact when said presser-foot has been lifted from the work.

11. In a shoe-sewing machine, the combination of a work support; a presser-foot; 70 a slidable support therefor; a spring acting on said support; a cam-controlled lever carrying said slidable support; and means preventing the cramping of said slidable support in its bearing in said lever when end 75 movement is imparted to said slidable member due to varying thicknesses of the work.

Signed by us at 746-7 Old South Bldg., Boston, Mass., this 29th day of November, 1919.
